ART OF CASTING

Filed Sept. 13, 1930

Inventor.

John Le May.

By Dyerforth, Lee, Christian & Wiles.

Atty's.

UNITED STATES PATENT OFFICE

JOHN LE MAY, OF AURORA, ILLINOIS, ASSIGNOR TO AURORA METAL COMPANY, OF AURORA, ILLINOIS, A CORPORATION OF ILLINOIS

ART OF CASTING

Application filed September 13, 1930. Serial No. 481,777.

This invention relates to improvements in the art of casting and is especially applicable to the casting of metal. The invention will be found of particular use in connection with die casting under pressure or under vacuum or reduced pressure.

Among the features of my invention is the provision of means for preventing the shortening of elongated cast members.

For the purpose of illustrating my invention I have shown the same as it could be used in connection with the casting of a worm, or grid. It is to be understood, however, that the invention can be used in connection with the casting of any elongated member where the prevention of shortening is desired.

In general, it may be stated that the particular feature of my invention is the insertion in the elongated member of a compression member to prevent such undesired shortening in length.

In those forms of devices embodying the features of my invention shown in the accompanying drawings,—

Figure 1 is a view in perspective of a separable mold adapted for casting a worm, Fig. 2 is a view taken as indicated by the line 2 on Fig. 1, Fig. 3 is a view similar to Fig. 2 showing the casting in place, Fig. 4 is a view of the completed worm, Fig. 5 is a vertical sectional view of a grid, Fig. 6 is a view of the completed grid, and Fig. 7 is a view taken as indicated by the line 7 on Fig. 6.

As shown in the drawings, a mold for casting a worm may consist of three portions, namely, the end portion 10, the center portion 11, and the end portion 12 containing the filling hole or gate 12^a. The center portion 11 contains the cavity 13 for casting the completed worm 14. It will be seen that if such a worm is cast out of some metal that has considerable shrinkage upon cooling the same will bind in the mold unless means to prevent such shortening in length are provided. In order to prevent such shortening in length I employ a compression member 15 (for example steel) which is embedded in the completed worm and provided with shoulders 15^a at the end over which the casting extends. This member 15 has a great resistance against

shortening in length and acts as a compression member to prevent the casting 14 from shortening in length when it cools.

The ends of the member 15 are preferably reduced in diameter and extend as indicated by 15^b, 15^b. These reduced ends are preferably inserted in holes 10^b and 12^b in the end portions 10 and 12, respectively, of the mold in order to hold the compression member 15 properly centered and spaced in the mold cavity 13 when the worm is cast. A suitable gate or filling hole 12^a may be provided in the end member 12 on the mold for the pouring of the metal. After the mold has been poured and after it has cooled, the end portions 10 and 12 of the mold may be removed and the completed worm 14 mounted on the compression member 15 removed from the central part 11 of the mold by screwing the same out. It is to be particularly noted that the casting 14 is long enough to cover the shoulders 15^a on the end of the compression member 15 so that such shoulders can take some of the pull of the casting 14 when the same tends to shorten in length.

The invention is also embodied in the apparatus shown in Figs. 5, 6 and 7 for the casting of a grid. For example, as here shown, it may be desired to cast a grid with the elongated bars 20, 20, joined by the connecting members 21, 21. Shrinkage in length of the elongated members 20 would shear off the member 21 or damage the same. In order to prevent such shrinkage or shortening in length of the members I cast in each of the same a compression member 22, for example steel. This compression member has as understood shoulders 22^a, 22^a, and the member 20 is long enough to cover these shoulders.

The mold as shown in Figs. 5, 6 and 7 may include two end pieces 23 and 24 and two separable central portions 25 (but one being shown in Fig. 5). The cavities in the central portions 25 for casting the members 20 are indicated by 26. The compression member 22 may be provided with extensions reduced in diameter as indicated by 22^b, said extensions being supported in suitable holes 23^a, 24^a in the end members 23 and 24 of the mold, respectively. It will be seen that when the

grid has been cast as shown in Figs. 6 and 7, the compression members 22 will be embedded in the elongated members 20 and the shoulders of the compression member also covered. This compression member being thus embedded in the elongated member 22 will prevent shortening of the same when it cools.

While I have shown and described certain embodiments of my invention, it is to be understood that it is capable of many modifications. Changes, therefore, in the construction and arrangement may be made without departing from the spirit and scope 15 of the invention as disclosed in the appended claim, in which it is my intention to claim all novelty inherent in my invention as broadly as possible in view of the prior art.

What I regard as new, and desire to secure 20 by Letters Patent, is:

In the art of casting an elongated member with laterally projecting parts, the method 25 consisting of providing a compression member having shoulders thereon, placing said compression member in the mold cavity, and casting metal about said compression member and over said shoulders, whereby the ends of said cast member upon cooling engage the shoulders of said compression member to prevent 30 said cast member from materially shortening and damaging said laterally projecting parts.

In witness whereof I have hereunto set my hand this 10th day of September, 1930.

JOHN LE MAY.
